(57) **CLAIM**

The ornamental design for a body for a portable air moving apparatus, as shown and described.

DESCRIPTION

FIG. 1 is a right side front perspective view of a body for a portable air moving apparatus showing my new design;
FIG. 2 is a right side rear perspective view thereof;
FIG. 3 is a front elevation view thereof;
FIG. 4 is a right side elevation view thereof;
FIG. 5 is a left side elevation view thereof;
FIG. 6 is a rear elevation view thereof; and,
FIG. 7 is a top plan view thereof.

The broken lines illustrate portions and environmental structure of the body for a portable air moving apparatus and form no part of the claimed design.
